CLAMP

Filed Jan. 27, 1927

INVENTOR

MAX MIRKIN

By *R. Miller*
J. & L. Co., Atty.

UNITED STATES PATENT OFFICE.

MAX MIRKIN, OF NEW YORK, N. Y.

CLAMP.

Application filed January 27, 1927. Serial No. 164,039.

This invention relates to improvements in clamps or fastening devices, and more particularly to a hand operated clamp adapted to securely hold two relatively movable members in fixed relation. For the sake of illustration, the device will hereinafter be described with relation to its application to the construction shown in my prior patent, No. 1,584,240, altho it is, of course, to be realized that I do not wish to be understood as limiting it to this application as it is obviously adaptable for many other purposes.

One object of the present invention is to provide a simple and practical clamp of the above general character which may be inexpensively manufactured and assembled.

A further object is to provide a clamp of the above character which will be reliable and efficient in use and operation to positively and securely hold the members in fixed position.

Other objects will be in part obvious and in part hereinafter pointed out in connection with the accompanying sheet of drawings illustrating a preferred embodiment of the present invention.

Referring to these drawings in detail, Fig. 1 is a perspective view showing the clamp in applied position.

Fig. 2 is a section on line 2—2 of Fig. 3.

Fig. 3 is a side elevational view.

In these drawings, let it be assumed that 5 indicates an object or material, such as the side wall of a container such as the bath tub shown in my prior patent to which the clamp is adapted to be attached. The body portion of the clamp is indicated at 6, and constitutes a normally vertically disposed wall or surface having one or more hooks, projections or other form of supporting devices 7, for example, to which a second article, not shown, may be adjustably suspended. The upper part of the clamp body is provided with a laterally or horizontally extending portion 8 which overlies the wall 5, a downwardly extending part 10, and a second reversely extending horizontal part 11, the latter forming a support for the actuating and clamping means. In the present case, these clamping means constitute or comprise L-shaped levers having a hand actuated portion 12 and a gripping or engaging portion 13, each lever being pivoted at its angle, as by means of rivets 14, to the horizontally extending supporting shelf 11 which is reinforced by plate 15 if

desired, which is bent as indicated to act as a stop for the levers. Thus, for example, when the actuating levers or hand portions 12 are in a position parallel to the face of the clamp 6, the engaging portions 13 almost bear against the inside wall of this face 6 and grip any intervening material therebetween, such, for example, the bath tub wall 5 as shown in Fig. 1. When the hand actuated parts 12 are moved outwardly towards each other, these gripping means 13 are released. Other forms of actuating levers may be employed if desired, such as will cause the gripping means to release when the handles are moved in reverse direction.

As herein shown, the clamp in operation is slipped over the main supporting article, such as the one indicated by the numeral 5, and then the actuating means 12 moved to cause the gripping portions 13 to hold the clamp in fixed position on its support. Obviously, the upper part of the member 5 instead of being a bead could be a line or rope, for example about which a fabric was adapted to be clamped.

Thus, the present invention comprises a simple and practical clamp designed to accomplish, among others, all of the objects and advantages herein set forth.

I claim:

1. In a device of the character described, in combination with a wall of a container or the like, a clamp to support an article from said wall and within the container comprising a body portion, a portion overlying said wall, and a reversely bent portion, gripping means comprising actuating members and gripping members swingable on said reversely bent portion in a plane parallel thereto, said gripping members adapted to grip the said wall against the body portion, said body portion being provided with means permitting attachment of the article thereto.

2. In a device of the character described, in combination with a wall of a container or the like, a clamp to support an article from said wall and within the container comprising a body portion, an overlying portion, a reversely bent portion, gripping means comprising actuating members and gripping members swingable on said reversely bent portion in a plane parallel thereto, said gripping members adapted to grip the said wall against the body portion, and a reinforcing plate co-operating with said gripping means and reversely bent portion to serve as a stop for

said actuating members when actuated in non-gripping direction, said body portion being provided with means permitting attachment of the article thereto.

5. A clamp comprising a body portion, an overhanging portion, and a laterally extending portion extending therefrom and carrying two pivoted L-shaped arms swingable in a plane parallel thereto, the ends of said arms comprising gripping portions, which when actuated by the other ends are adapted to grip an intervening object against the body portion.

10. A clamp comprising a body portion, an

overhanging portion, a laterally extending portion extending therefrom and carrying two pivoted L-shaped arms swingable in a plane parallel thereto, the ends of said arms comprising gripping portions, which when actuated by the other ends are adapted to grip an intervening object against the body portion, and a reinforcing plate cooperating with said laterally extending portion and said arms to serve as a stop for said arms when actuated in non-gripping direction.

Signed at New York, New York, this 25th day of January, 1927.

MAX MIRKIN.
